LOWER ALKYLENE AND LOWER ALKYLENE-PHENYLENE-LOWER ALKYLENE POLYAMINE BIS N,N' LOWER ALKYLENE DI AND TRI CARBOXYLIC ACIDS, ESTERS, SALTS, AND CHELATES

William M. Ramsey, Downey, and Charles Kerzerian, Los Angeles, Calif., assignors to Victor Chemical Works, Chicago, Ill., a corporation of Illinois
No Drawing. Filed June 17, 1959, Ser. No. 820,872
25 Claims. (Cl. 260—429)

This invention relates to products, and methods of producing same, from the group consisting of:

(a) A compound essentially of the formula:

wherein A_1 and A_2 are the same or different members of the group consisting of alkylene and alkylene-phenylene-alkylene groups; Y_1 , Y_2 , and Y_3 are members of the same or different alkyl group or hydrogen, and at least one of Y_1 and Y_2 is an alkyl group; k is a positive integer of not less than 1 and not more than 7; Z_1 and Z_2 are the same or different bis-adduction reaction residues of a member of the class consisting of unsaturated polycarboxylic acids, lactones, and salts (includes acid addition salts and salts having a cation bonded to a carboxyl group) thereof;

(b) Chelates comprising the product of (a) and a polyvalent metal ion; and

(c) esters comprising the product of (a) and a lower alkyl substituent bonded to at least one carboxyl group.

Stated in a different manner, this invention relates to bis-adduction products, and methods of producing same, from the group consisting of:

(a) A compound essentially of the formula:

wherein A_1 and A_2 are the same or different members of the group consisting of alkylene and alkylene-phenylene-alkylene groups; Y_1 , Y_2 , and Y_3 are members of the same or different alkyl group and hydrogen, and at least one of Y_1 and Y_2 is an alkyl group; k is a positive integer of not less than 1 and not more than 7; R_2 and R_4 are members of the class consisting of hydrogen, lower alkyl groups, $-COOM$ groups, and lower alkylene- $COOM$ groups; R_1 and R_3 are members of the class consisting of lower alkylene groups and lower alkylene groups having an additional free bond; n is a positive integer of not less than 1 and not more than 2; R_6 and R_7 are lower alkylene groups when n is 1; R_8 and R_9 are members of the class consisting of hydrogen, lower alkyl radicals, and lower alkylene- $COOM$ groups; and M in the above formula is the same or different radical from the class consisting of hydrogen, organic base radicals, inorganic base radicals, and lower alkyl radicals;

(b) Chelates comprising the compound of (a) and a polyvalent metal ion;

(c) Salts (i.e., includes acid addition salts) of the compound of (a); and

(d) Lactones of (a).

The term "alkylene" is herein (includes claims) intended to include alkyl and substituted alkyl radicals having an additional free bond. The terms alkenyl, "alkyl" and "phenylene" are herein (includes claims) intended to

2

include substituted alkenyl, alkyl and phenylene groups, respectively. The term "carboxyl" is herein intended to include the

group. The phrase "unsaturated polycarboxylic acids" is sometimes herein intended to include acyclic ethylenically unsaturated polycarboxylic acids, lower alkyl polycarboxylic acids, salts thereof, and their anhydrides.

Y_1 , Y_2 and Y_3 in the above formulae may be hydrogen or an alkyl group such as unsubstituted alkyl, alkylaryl, hydroxyalkyl, hydroxyalkylaryl, hydroxyalkyloxyaryl, carboxyalkyl and alkylcarboxylates, hydroxyalkylpolyoxyalkyl (e.g., $-(CH_2CH_2O)_4H$), and alkylphosphonic acid alkylphosphonate, alkylsulfonic acid, and alkylsulfonate radicals. In the formulae, A_1 and A_2 are the same or different members of the group consisting of lower alkylene and lower alkylene-phenylene-lower alkylene radicals.

R_2 and R_4 in the above formula may be hydrogen, a lower alkyl group, a lower alkylene- $COOM$ group, or a $-COOM$ group. R_1 and R_3 are lower alkylene groups such as methylene or a lower alkylene group having an additional free bond; R_6 and R_7 are lower alkylene groups such as methylene. R_8 and R_9 may be hydrogen, a lower alkyl radical, or a lower alkylene- $COOM$ radical. M may be the same or different radical from the group consisting of hydrogen, an organic base radical such as triethanolamine, an inorganic base radical such as sodium and $-NH_4$, or a lower alkyl ester radical such as $-CH_2-CH_3$.

FIRST STEP IN PREPARATION OF OUR PRODUCTS

Products of the above formulae may be produced by first reacting an organic poly primary amine with one mole of a member from the group consisting of unsaturated polycarboxylic acids, salts thereof (e.g., alkali metal and tertiary amine salts) and esters thereof, for each primary amine group present in the organic poly primary amine, as shown in copending Kezerian and Ramsey application entitled "Bis-Adduction Products and Methods of Preparing Same," Ser. No. 800,116, filed March 18, 1959. The adduction reaction involves a reaction between the nitrogen atoms of the amine and the double bond of the acid, ester or salt thereof. This reaction may be illustrated by the following equation:

where R_1 and R_2 are hydrogen or lower alkyl groups and M is as defined above. R_5 in the above formula may be a member of one of the following groups: an alkylene radical such as exemplified by ethylene, hexamethylene, and 2-hydroxy-propylene; a phenylene-lower alkylene-phenylene radical such as methylenediphenylene; a lower alkylene-phenylene-lower alkylene radical such as xylene; and a

(a) that is repeated as desired (the term "desired" may be zero) number of times, (b) wherein each lower alkylene radical may be the same or different, and (c) wherein each repeating radical need not be the same as the preceding one. The

may be illustrated by the following groups:

and

The salts formed in accordance with the above reaction may be converted to the free amino acids by treatment with stronger acids. In most cases the free amino acid is precipitated and may be separated by filtration. In some instances where the free amino acid is soluble it may be separated by ion exchange methods.

As another illustration of the above adduction reaction, itaconic acid may be reacted with triethanolamine to form a salt and the salt may be then reacted with p,p'-methylene-dianiline to form p,p'-di-N-pyrrolidone-2,4-carboxylic acid. This reaction is shown below:

Obviously, mixed or unsymmetrical amino acid products may be produced in reactions by employing mixtures of different unsaturated polycarboxylic starting materials.

The unsaturated polycarboxylic acids which are suitable for use in producing the compounds of the above reaction include aconitic, citraconic, itaconic, maleic, fumaric, methylitaconic, glutaconic, methylglutaconic, muconic acids, and the like, their salts, anhydrides, nitriles, etc. The acids are characterized by the presence of the 1,4-conjugated moiety:

Suitable organic poly primary amines for use in the above reaction include ethylenediamine, diethylenetriamine, tetraethylenepentamine, propylenediamine, hexamethylenediamine, beta hydroxypropylene-diamine, 2,2'-diaminodiethyl ether, 2,2'-diaminodiethyl sulfide, phenylenediamines, 2,2', 2"-triaminotriethylamine, benzidine, diaminocyclohexane, diaminophenol, polyglycoldiamine, lysine, ornithine, methylenedianiline, o-aminoethyl aniline, ammelene, melamine, tris-3-aminopropylamine, tris-2-aminoethylamine, etc.

The process for the preparation of the adduction products of the above reaction is accomplished by heating a basic aqueous solution or melt of the poly primary amine with the unsaturated polycarboxylic acid for a period of time sufficient to complete the reaction (from a few hours to a few days). The molecular proportions of the reactants are approximately one mole of the unsaturated polycarboxylic acid per primary amine group present in the poly primary amine. The alkalinity of the reaction mixture is established and maintained by means of a strong inorganic base or nonreactive strong organic base. Suitable bases include NaOH, KOH, triethylamine, triethanolamine, and the like. The basicity of the reaction mixture is preferably held at a pH above 9.5. The speed

of the reaction may be varied to some extent by varying the temperature and pressure conditions under which the reaction is carried out. In general, the most satisfactory procedure is to heat the mixture to a refluxing temperature at atmospheric pressure for a period of at least several hours. It is essential to maintain alkaline reaction conditions during such polyaddition reactions in order to prevent unnecessary complex side reactions involving carboxylic hydrogen with excess amine groups.

10 SECOND STEP IN PREPARATION OF OUR PRODUCTS

The products of this invention are prepared from the products of the reaction referred to above as the first step, by reacting the hydrogen atom of one or more of the secondary amino groups

15

of the product of the first step with products that replace the hydrogen with alkyl groups such as hydroxyalkyl, hydroxyalkylaryl, carboxyalkyl, hydroxyalkylpolyoxyalkyl, and alkylphosphonic groups.

20 The product of the first step may be reacted with products such as chloropropanol, ethylene chlorohydrin, chloropropanediols, benzyl chloride, dodecyl chloride, stearoyl chloride, ethylene dibromide, tetraglycol chloride, iodobenzene, chloronaphthalene, chlorophenol, cyclohexyl bromide, chlorosuccinic acid, chloroacetic acid, chlorobutyric acids, phenylchloroacetic acid, chloromethylphosphonic acid, diphenylphosphorus oxychloride, ethylene oxide, styrene monoxide, epichlorohydrin, glycidol, phenyl glycidol, allyl alcohol, crotonic acid, ethylene cyanohydrin, acetone cyanohydrin, hydroxypropionitrile, acrylonitrile, hydroxymethane sulfonic acid (formalin plus sodium bisulfite) and glycidol phenyl ether.

25 Examples I-VIII, infra, illustrate the first step in our method wherein an organopolyprimary amine is reacted with one mole of a member from the group consisting of unsaturated polycarboxylic acids or lactones, salts thereof, and esters thereof, for each primary amine group present in the organopolyprimary amine.

30 Examples IX-XXXIV, infra, illustrate either (a) the second step of our method wherein the hydrogen atom of at least one of the secondary amino groups of the product of step one is replaced with various alkyl groups (includes substituted alkyl groups), or (b) the preparation of derivatives of (a).

35 Examples XXXV-XXX, infra, show some of the outstanding properties of our products and the uses to which they may be applied. Example XXXV shows that these products are outstanding chelants or chelating agents. Example XXXVI shows that they are effective in removing rust and oxide coatings from metal surfaces. Example XXXVII shows that these products inhibit the destructive effects of mineral acid on iron. Example XXXVIII illustrates their use in resin formulations. Example XXXIX discloses the use of our products in metal coating baths. Example XXX illustrates their use in treating plant chlorosis.

EXAMPLE I

Ethylenediamine Bis-N,N'-Succinic Acid

70 75 400 grams of maleic anhydride (4.1 moles) were added to 400 ml. water, and the mixture was set aside for one hour. This mixture was neutralized slowly under a reflux condenser, while cooling (75-85° C.) and stirring during

Ethylenediamine is only the first in a varied series of polyamines that yield insoluble adducts with maleic acid. Repeating the conditions of Example I, diethylenetriamine was substituted for ethylenediamine, as is described in the following example.

The reaction was carried out as described in Example I, combining 200 g. of maleic anhydride (2.02 moles) in 100 ml. of water with 320 g. of 50% by weight NaOH. This solution was then treated with 103 g. of diethylenetriamine (1.0 mole) and was refluxed for 48 hours. The reaction mixture had to be diluted to 800 ml. during the reflux period so as to keep the reactants and product in solution.

The reaction solution was cooled and then acidified with 320 ml. of concentrated HCl to a pH of 3.3. Upon setting overnight, the product, a fine white microcrystalline product, was filtered and washed with two, 100 ml. portions of water. This material was dried at 100-105° C. to a white free-flowing powder. Yield: 180 g., 57% of theory (335 g.); M.P.: 208-210° C.

The sample of diethylenetriamine bis-N,N'-succinic acid was recrystallized in the normal manner, that is, by dissolving it first in NaOH solution, followed by reprecipitation in the cold at a pH of 3.3 with concentrated HCl. The resulting product was filtered and washed thoroughly with water. The product was divided into fraction (A) which was air dried to a constant weight and fraction (B) which was dried at 100° C. to a constant weight.

Analytical data.—

- (A) $\text{C}_{12}\text{H}_{21}\text{N}_3\text{O}_8 \cdot \text{H}_2\text{O}$ —M.W. determined by pH titration: Found 358, theory 353. Percent N found: 11.72, theory 11.90.
 (B) $\text{C}_{12}\text{H}_{21}\text{N}_3\text{O}_8$ —M.W. determined by pH titration: Found 340, theory 335. Percent N found: 12.49, theory 12.54.

EXAMPLE IV

Tetraethylenepentamine Bis-N,N^{IV}-succinic Acid

The reaction was again carried out in the same manner described in Example I, that is, by combining 200 g. (2.04 mole) of maleic anhydride in 100 ml. of water with 320 g. of 50% by weight NaOH. The hot solution was treated with 189 g. (1.0 mole) of tetraethylenepentamine, and was then refluxed for 28 hours.

The final reaction solution was cooled, filtered, diluted to 1 liter and stored as a 1 molar solution of tetrasodium tetraethylenepentamine bis-N,N^{IV}-succinate. Since acidification does not liberate the water soluble free acid, a 0.1 mole aliquot (100 ml.) of the tetrasodium salt was passed through a column of Amberlite IR-100 cation resin (acid form). The 800 ml. of acidic effluent were concentrated under vacuo to a syrup, which was washed with ethanol and desiccated for several days until it

solidified. The brown solid was insoluble in ethanol and acetone, but soluble in water. The product was very hygroscopic.

A 4.9871 g. sample of desiccated acid was dried to constant weight at 100° C. The product fused, foamed, and then hardened to a brittle mass. The 0.5713 g. loss of water left a 4.4158 g. residue. This would be the theoretical loss from a trihydrate.

Analytical data.— $\text{C}_{16}\text{H}_{31}\text{O}_8\text{N}_5$ —Percent N: Found 14.72; theory 16.61.

EXAMPLE V

1,6-Hexamethylenediamine Bis-N,N'-succinic Acid

The reaction was carried out in the same manner as described in Example I, that is, by combining 100 g. of maleic anhydride (1.02 moles) in 200 ml. of water with 160 g. of 50% by weight NaOH. The hot solution was then treated with 58 g. (0.5 mole) of 1,6-hexamethylenediamine, and was refluxed for 48 hours.

The final liquor was cooled, and acidified with 160 ml. of concentrated HCl to a pH of 2.6. The white crystalline product was allowed to settle for several hours, and was then filtered and washed with 800 ml. of water. The crystals were dried to constant weight at 105° C. The yield was 75 g., 64.6% of the theoretical yield of 116 g. A 60 g. sample of the above product was dissolved in 10% NaOH, and reprecipitated by acidification to a pH of 2.6 with concentrated HCl. The product precipitated in two distinctly separate fractions.

The first crop (No. 1) of crystals separated immediately from the acidified solution. This crop was collected, washed, and dried at 105° C. The yield was 10 g., 16.6% of theory.

A second crop (No. 2) of crystals separated from the clear filtrate upon standing for 15 minutes. The yield of dried product was 35 g., 58% of theory. This second crop was divided into two portions: (A) which was dried in air at room temperature, and (B) which was dried at 105° C. to a constant weight.

Analytical data of crop No. 2.—(2A) $\text{C}_{14}\text{H}_{24}\text{N}_2\text{O}_8$: $2\text{H}_2\text{O}$ —Percent N: Found 6.97; theory 7.11. (2B) $\text{C}_{14}\text{H}_{24}\text{N}_2\text{O}_8$ —Percent N: Found 7.63; theory 7.82. M.W. determined by pH titration: Found 328; theory 348. Inflection pH was 7.0.

Crop No. 1 appeared to be the product formed by an impurity present in the 1,6-hexamethylenediamine, namely, 1-hydroxy-6-aminohexane. This probably results from the following side reaction:

This by-product may be separated from the desired bis-adduct by fractional crystallization as shown above.

9

EXAMPLE VI

*Diethylenetriamine Bis-N,N'-Tricarballylic Acid*174 grams ofaconitic acid (1.0 mole) were treated with 40 ml. of water, followed by 450 g. of triethanolamine (3.0 moles) and, finally 51.5 g. of diethylenetriamine (0.5 mole). The thick mixture was then set aside to digest under gentle reflux at 125-130° C. for 36 hours.

The reaction solution, a dark red-brown syrup, was diluted to 1 liter and was used as a 0.5 molar solution of the product.

A 200 ml. (0.1 mole) aliquot of the reaction solution were treated with 24 g. (0.6 mole) of NaOH and 1 liter of ethanol. Prolonged stirring gave a thick oily sediment of hexasodium salt, which was washed free of triethanolamine with two 50 ml. portions of ethanol and was dissolved in 200 ml. of water. This solution was passed through a column of Amberlite IR-100 cation exchange resin (acid form). The acidic effluent was concentrated under vacuo to 65 ml., then treated with 800 ml. of ethanol. A brown solid separated, which was dried in a vacuum desiccator. The yield was 8 g., 21% of theoretical 33.8 g. yield. Its decomposition point was approximately 230° C.

Analytical data. — $\text{C}_{16}\text{H}_{25}\text{N}_3\text{O}_{12}$ — Percent N: Found 10.91; theory 9.31. M.W. determined by pH titration: Found 447; theory 451. Inflections at pH of 6.8 and 10.5

The position of adduction of the primary amine to the unsaturation of aconitic acid may be either α or β . Possibly the beta isomer may predominate.

and/or

EXAMPLE VII

*p,p'-Methylenedianiline Bis-N,N'-Succinic Acid*10 The aryl amine incorporated into this reaction is water insoluble, as well as being insoluble in any alkaline aqueous media. Thus, triethanolamine was again used as both solvent and neutralizing base.

15 100 grams of maleic anhydride (1.02 moles) were added to 25 ml. of water and allowed to hydrolyze slowly to maleic acid. The mass of crystals were gradually dissolved in 330 g. (2.2 moles) of triethanolamine. Finally, 99 g. (0.5 mole) of p,p'-methylenedianiline were added and the reaction mixture digested under reflux at 130-140° C. for 26 hours. The reaction solution remained as one clear phase.

20 The solution was cooled and diluted with 250 ml. of water. Since the reaction solution remains as one phase, this is evidence that the amine has reacted, otherwise it would have separated on dilution.

25 The diluted solution was acidified with 183 ml. of concentrated HCl (2.2 moles). A gray oil separated immediately and was decanted free of the mother liquor. This residue was washed with 200 ml. of water, dissolved in 280 ml. of water containing 80 g. (2.0 moles) of NaOH, and reprecipitated with 166 ml. of concentrated HCl (2.0 moles). The residue was again decanted free of mother liquor, washed with three 200 ml. portions of water and two 150 ml. portions of ethanol. The free acid solidified when desiccated; however, the surfaces turned red when exposed to air, evidencing oxidation. The yield was 150 g., 70% of the theoretical 215 g. yield.

EXAMPLE VIII

*Diphenylmethane p,p'-Di-N-Pyrrolidone-2,4-Carboxylic Acid*55 120 grams of itaconic acid (0.92 mole) were added to 10 ml. of water, and the resulting salt was treated with 300 g. of triethanolamine (2.0 moles). The slurry was heated and stirred until completely dissolved. The resultant viscous solution was treated with 91 g. of p,p'-methylenedianiline (0.46 mole) and digested under gentle reflux at 120-130° C. for 48 hours. The reaction mixture, which contained some insolubles, was diluted to 600 ml., and filtered through a pad of diatomaceous earth. The clear filtrate was then acidified with 165 ml. of concentrated HCl. The oil, which separated, was decanted free of mother liquor, washed with two 100 ml. portions of water, and was then redissolved in 250 ml. of water containing 80 g. (2.0 moles) of NaOH. The product was reprecipitated with 165 ml. of concentrated HCl (2.0 moles), washed with two 100 ml. portions of water, and was then dried in a vacuum desiccator for several days. The final product was a dark-brown crystalline mass. The yield was 40 g., 21% of the theoretical 194 g. yield. The melting point was 200-210° C.

60 *Analytical data.* — $\text{C}_{23}\text{H}_{22}\text{N}_2\text{O}_6$ — Percent N: Found 6.92; theory 6.64. M.W. determined by pH titration: 65 Found 458; theory 422. Inflections at pH of 9.0.

11
EXAMPLE IX

Ethylenediamine Bis-N,N'-2-Hydroxyethyl Bis-N,N'-Succinic Acid ("EDDSDE")

292 g. (1.0 mole) of ethylenediamine bis-N,N'-succinic acid were added to 250 ml. of water containing 320 g. of 50% by weight NaOH (4.0 moles). The solution was stirred at 60–70° C. and was treated dropwise with 161 g. of chlorohydrin (2 moles) and also 160 g. of 50% NaOH (2 moles) while maintaining a solution that was alkaline to pH Hydron paper (pH of 11–12). Upon the completion of this addition (1/2–1 hour), the reaction temperature was raised to boiling for 10 minutes, cooled, and acidified to a pH of 2.0 with 320 ml. of conc. HCl. The liquor was filtered, seeded with product crystals, and stirred occasionally for 48 hours. The white fluffy product was filtered, washed with 100 ml. of water and dried in air to a constant weight. A yield of 260 g. was obtained, 68.4% of the theoretical 380 g. yield. The product had a M.P. of 168.5–169° C. (d).

An alternate name for this product is ethylenediamine bis-N,N'-ethanol-bis-N,N'-succinic acid.

EXAMPLE X

Ethylenediamine Bis-N,N'-2-Hydroxyethyl Bis-N,N'-Succinic Acid

292 g. (1.0 mole) of ethylenediamine bis-N,N'-succinic acid were dissolved in 400 ml. of water containing 320 g. of 50% by weight NaOH (4.0 moles). The solution was stirred at 55° C. and was treated dropwise with 190 g. of chlorohydrin (2 1/2 moles), while maintaining the pH at 10.5 with the aid of a pH meter. Upon completion of the addition (one hour) and one hour of digestion at 55° C., the reaction solution was cooled to 25° C., and was acidified with 330 ml. of concentrated HCl to a pH of 2.0. The liquor was seeded with the product crystals, and was stirred occasionally for 3 days. The white fluffy product was filtered, washed with 200 ml. of water, washed with 100 ml. of ethanol, and was then oven dried at 90° C. to a constant weight. A yield of 240 g. was obtained. At the end of seven weeks, the total product recovered increased to a yield of 290 g., 80.1% of the theoretical yield of 362 g. (monolactone).

When the above referred to white fluffy product is initially precipitated, it is in the form of the free acid. However, when this crystalline tetra-acid is dried in an oven at approximately 90° C., the acid is dehydrated to a monolactone, as follows:

Further drying of the monolactone up to 125° C. does not result in any further loss in weight, thus indicating

that the preparation of a dilactone requires more severe conditions. The presence of the lactone structure may be evidenced by the test described in "Spot Tests," F. Feigl (Elsevier, 1939), pages 295–297. This test procedure gives a positive test with the lactone shown in the above formula. When a pH titration of the lactone reaches a pH of 10, there is a downward shift in pH which can be attributed to the slow hydrolysis of the lactone and liberation of free carboxyl groups. The physical characteristics of the lactone do not differ from those of the free acid in any noticeable respect.

EXAMPLE XI

Ethylenediamine Bis-N,N'-2-Hydroxyethyl Bis-N,N'-Succinic Acid

272 g. (1.0 mole) of ethylenediamine bis-N,N'-succinic acid were slowly added to 500 ml. of water containing 496 g. of sodium carbonate monohydrate (4.0 moles). The solution was stirred at 65° C. and treated dropwise with 160 g. of chlorohydrin (2.0 moles) over a one hour period. Upon completion of the addition, the solution was warmed slowly while stirring to 90° C., was cooled, and was slowly acidified to a pH of 2.0 with 450 ml. of concentrated HCl. The slurry was filtered and the filtrate seeded with product crystals. The mixture was stirred occasionally for several hours and was set aside for 24 hours. The white product was filtered, washed with 100 ml. of water, washed with 100 ml. of ethanol, and then dried at 90° C. to a constant weight. A yield of 120 g. was obtained, 33% of the theoretical yield of 362 g. (monolactone).

The typical analysis for the free acid, and the monolactone of Example X are tabulated below.

Total N determination.—EDDSDE monolactone—C₁₄H₂₂N₂O₉—Percent N: Found 7.68; theory 7.73. EDDSDE free acid—C₁₄H₂₄N₂O₁₀—Percent N: found 7.16; theory 7.37.

Titration data.—Monolactone¹—M. wt.: Found 359.5; theory 362. Inflections at pH values of 10.30, 7.25. Free acid—M. wt.: Found 381; theory 380. Inflections at pH values of 10.30, 7.25 (4th and 3rd COOH).

Solubility data.—Monolactone—0.382 g./100 ml. H₂O at 27° C. Free acid—0.303 g./100 ml. H₂O at 27° C.

The free acid and monolactone are insoluble in alcohol, acetone, dioxane, dimethyl formamide, diethylene glycol, and many common organic solvents.

The free acid may lactonize in boiling water systems; however, the sodium salt may be boiled in solution for several days with no noticeable effect. The free acid may be isolated by drying the product crystals in air without the application of heat.

The following example describes the substitution of ethylene oxide for chlorohydrin.

EXAMPLE XII

Ethylenediamine Bis-N,N'-2-Hydroxyethyl Bis-N,N'-Succinic Acid

292 g. of ethylenediamine bis N,N'-succinic acid were

¹ Dissolved in NaOH, then back titrated with HCl.

13

dissolved in 300 ml. of water containing 320 g. of 50% by weight NaOH (4.0 moles). The solution was diluted to 1 liter, permitted to set, the pH was adjusted to 10.6, and the solution was heated to 60–65° C. While agitating and maintaining this temperature, a fine stream of ethylene oxide gas was introduced through a perforated polyethylene tube. When the reaction was complete after 2 hours, the solution was warmed to 95° C., cooled to room temperature, and acidified to a pH of 2.0 with 300 ml. of concentrated HCl. The reaction solution was seeded with product crystals, occasionally stirred, and the pH of the solution was left undisturbed for 72 hours at room temperature. The product was filtered, washed with 200 ml. of water, washed with 100 ml. of ethanol, and dried at 100° C. to form the dry monolactone product. A yield of 255 g. (M.P. 168–170° C. (d)) was obtained, 70.4% of the theoretical yield of 362 g. (monolactone).

Ethylenediamine bis-N,N'-2-hydroxyethyl bis-N,N'-succinic acid forms a crystalline tetrasodium salt, in the form of a decahydrate.

EXAMPLE XIII

Tetrasodium Ethylenediamine Bis-N,N'-2-Hydroxyethyl Bis-N,N'-Succinate Decahydrate

181 g. (0.5 mole) of ethylenediamine bis-N,N'-2-hydroxyethyl bis-N,N'-succinic acid (monolactone) were stirred into 160 g. of 50% by weight NaOH (2 moles). The temperature was kept below 60–70° C., and, finally, 50 ml. of water were added. The warm solution was seeded with several large crystals and was allowed to cool.

At the end of 24 hours, the undisturbed liquor produced large well-formed transparent crystals. These were broken up, filtered, and air-dried cautiously to the decahydrate. A yield of 221 g. was obtained, 68.2% of the theoretical yield of 324 g. The saturated mother liquor was 32.5° Bé. at 27° C.

A slurry of granular crystals rather than large lumps may be obtained by stirring the warm liquor after seeding, and then cooling slowly the liquor for several hours. The resulting crystals are uniform in size, similar to granular sugar.

If it is desired to dry the decahydrate to the anhydrous form, it must be done with care since the decahydrate easily melts at 90° C. to a non-crystallizing syrup. The crystalline hydrate may be placed in an oven and the temperature raised slowly from 30° C. to 100° C. over a 24 hour period (thin beds of material dry most efficiently).

A typical analysis of the tetrasodium ethylenediamine bis-N,N'-2-hydroxyethyl bis-N,N'-succinate, hydrate and anhydrous product follows:

Decahydrate.— $\text{C}_{14}\text{H}_{20}\text{N}_2\text{O}_{10}\text{Na}_4 \cdot 10\text{H}_2\text{O}$ —Percent N: Found 4.15, theory 4.32%. Titration data—Mol. Wt.: Found 654, theory 648. Inflections at pH values of 10.75, 7.15.

Anhydrous.— $\text{C}_{14}\text{H}_{20}\text{N}_2\text{O}_{10}\text{Na}_4$ —Percent N: Found 5.98, theory 5.98%. Titration data—Mol. Wt.: Found 481, theory 468. Inflections at pH values of 10.75, 7.15.

Drying tests of the decahydrate resulted in a 27.23% loss of water, compared to a theoretical loss of 27.77%.

The insoluble dibaum salt was prepared in the next example.

14

EXAMPLE XIV

Dibaum Ethylenediamine Bis-N,N'-2-Hydroxyethyl Bis-N,N'-Succinate

36 g. (0.1 mole) of ethylenediamine bis-N,N'-2-hydroxyethyl bis-N,N'-succinic acid (monolactone) were added to 100 ml. of water. 200 ml. of 1.0 molar BaCl_2 solution were then added. The slurry was stirred, and treated with 32 g. of 50% by weight NaOH (0.4 mole). The slightly soluble product soon crystallized-out, and was filtered, was washed with 50 ml. of hot water, was washed with 50 ml. of ethanol, and was then dried at 120° C. to a constant weight. A yield of 45 g. was obtained, 70% of the theoretical yield of 65 g.

Analytical data.— $\text{C}_{14}\text{H}_{20}\text{N}_2\text{O}_{10}\text{Ba}_2$ —Percent N: Found 4.15, theory 4.30%.

The dibaum salt may also be easily prepared by adding BaCl_2 solution to a solution of the tetrasodium salt of the above compound.

EXAMPLE XV

Lead Dihydrogen Ethylenediamine Bis-N,N'-2-Hydroxyethyl Bis-N,N'-Succinate

37.9 g. (0.1 mole) of lead acetate trihydrate were dissolved in 200 ml. of water, and the solution was treated with 36.2 g. of ethylenediamine-bis-N,N'-ethanol bis-N,N'-succinic acid (0.1 mole as monolactone) with stirring. After stirring for a few hours, the mixture solidified. The product was added to 1 liter of boiling water and filtered. The filtrate, on cooling, yielded a crop of crystals which were recrystallized from boiling water (1 liter). The product was dried under vacuo at 90–100° C. The product was slightly soluble in water and was very soluble in alkaline solutions.

Analytical data.— $\text{C}_{14}\text{H}_{22}\text{N}_2\text{O}_{10}\text{Pb}$ —Percent N: Found 4.83, theory 4.79%.

A slight variation in the procedure made it possible to isolate the more soluble zinc chelate.

EXAMPLE XVI

Zinc Dihydrogen Ethylenediamine Bis-N,N'-2-Hydroxyethyl Bis-N,N'-Succinate

22 g. of (0.1 mole) of zinc acetate dihydrate were dissolved in 200 ml. of water. 36.2 g. of ethylenediamine bis-N,N'-ethanol bis-N,N'-succinic acid (0.1 mole as monolactone) were then added. The admixture was stirred and a nearly clear solution was formed. The solution was filtered and concentrated by boiling it in vacuo to 50 ml. The addition of ethanol precipitated a solid which was filtered, dissolved in 40 ml. of hot water, cooled, and reprecipitated with ethanol. The white semi-

crystalline product was filtered and was dried at 80° C. in vacuo for 3 hours.

Analytical data.—C₁₄H₂₂N₂O₁₀Zn—Percent N: Found 6.25, theory 6.31%.

EXAMPLE XVII

Cupric Dihydrogen Ethylenediamine Bis-N,N'-2-Hydroxyethyl Bis-N,N'-Succinate

20 g. (0.1 mole) of copper acetate monohydrate were dissolved in 1.5 l. of water. 36.2 g. of ethylenediamine bis-N,N'-ethanol-bis-N,N'-succinic acid (0.1 mole as monolactone) were then added. The suspension was boiled to dissolve all solids, filtered hot, and then cooled. The solution yielded a crop of fine blue crystals (a second crop may be obtained by treating the mother liquor). The product was dried in a vacuum oven at 80° C. to a constant weight.

Analytical data.—C₁₄H₂₂N₂O₁₀Cu—Percent N: Found 6.31, theory 6.20%.

The ferric chelate is very soluble; however, it was prepared in the following example.

EXAMPLE XVIII

Ferric Hydrogen Ethylenediamine Bis-N,N'-2-Hydroxyethyl Bis-N,N'-Succinate

19.5 g. (0.1 mole) of 98% assay basic ferric acetate were added to a slurry of 36.2 g. of ethylenediamine bis-N,N'-ethanol bis-N,N'-succinic acid (0.1 mole as monolactone) in 100 ml. of water. The mixture was stirred until it was dissolved and was then filtered through diatomaceous earth. When the clear liquid was treated with 400 ml. of ethanol, a green-yellow solid deposited out on standing. The product was filtered out, washed with 50 ml. of ethanol, and dried under vacuo at 65° C. to a constant weight. A yield of 26 g. was obtained, 59% of the theoretical yield of 44 g.

Analytical data.—C₁₄H₂₁N₂O₁₀Fe—Percent N: Found 6.10, theory 6.47%. Percent ash: Found 21.40, theory 18.45% as Fe₂O₃.

EXAMPLE XIX

Diethylenetriamine Tris-N,N',N''-2-Hydroxyethyl Bis-N,N''-Succinic Acid ("DTHDS")

168 g. (0.5 mole) of diethylenetriamine bis-N,N''-succinic acid were dissolved in 300 ml. of water containing 160 g. of 50% NaOH (2.0 moles). The solution was diluted to 1 liter, warmed to 60° C., and adjusted to a pH of 10.75. While stirring, a rapid fine stream of ethylene oxide gas was introduced.

When the reaction was completed, the reaction liquor

was warmed to 90° C., filtered, cooled, diluted to 1 liter, and stored as a 0.5 molar solution of tetrasodium diethylenetriamine tris-N,N',N''-2-hydroxyethyl bis-N,N'-succinate.

EXAMPLE XX

Tetraethylenepentamine Penta-N,N',N'',N''',N''''-2-Hydroxyethyl Bis-N,N''''-Succinic Acid ("TPHDS")

179 g. (0.5 mole) of tetraethylenepentamine bis-N,N''''-succinic acid were dissolved in 500 ml. of H₂O containing 160 g. of 50% NaOH (2.0 moles). The solution was stirred, warmed to 60° C. and its pH adjusted to 11.0. While maintaining these conditions, a fine stream of ethylene oxide gas was introduced.

When the reaction was completed, the reaction liquor was warmed to 90° C., cooled, filtered, diluted to 1 liter, and stored as a 0.5 molar solution of tetrasodium tetraethylenepentamine penta-N,N',N'',N''',N''''-2-hydroxyethyl-bis-N,N'-succinate.

EXAMPLE XXI

Tetraethylenepentamine Penta-N,N',N'',N''',N''''-2-Hydroxyethyl Bis-N,N''''-Succinic Acid, Penta Hydrochloride

45 100 ml. aliquot of a 0.5 molar solution of tetrasodium tetraethylenepentamine - penta - N,N',N'',N''',N''''-2-hydroxyethyl bis-N,N''''-succinate (0.05 mole) were passed through a column of Amberlite IR-100C cation exchange resin (acid form) to remove sodium ions. The effluent of free acid was then treated with 21 ml. of conc. HCl (0.25 mole), concentrated in vacuo to 60 ml., and then added in a cold state to 400 ml. of acetone. The residue was washed twice with 100 ml. of acetone, and the resulting solid was dried under vacuo at 70° C. to a constant weight. A yield of 25 g. was obtained, 61% of the theoretical yield of 41 g.

Analytical data.—C₂₈H₅₆N₈O₁₃Cl₅—Percent N: Found 8.39, theory 8.52%.

The 2,3 propylene-glycol radical, which is more hydrophylic than ethanol, may be introduced by means of 1-chloro 2,3-propanediol or by reaction with epichlorohydrin.

EXAMPLE XXII

Tetrasodium Ethylenediamine Bis-N,N'-2,3-Dihydroxypropane Bis-N,N'-Succinate ("EDPDDS")

292 g. (1.0 mole) of ethylenediamine bis-N,N'-succinic acid were dissolved in 500 ml. of water containing 320 g. of 50% by weight NaOH. The solution was adjusted to a pH of 10.75, warmed to 60° C., and stirred vigorously. A total of 221 g. (2.0 moles) of 1-chloro-2,3-propanediol and 160 g. (2.0 moles) of 50% NaOH were added dropwise into and blended with the agitated solution. During the addition, the pH and temperature were maintained at their original values. After 1/2 hour, the reaction solution was cooled, filtered, diluted to 2 liters, and stored as a 0.5 molar solution of tetrasodium ethylenediamine bis-N,N'-2,3-propanediol bis-N,N'-succinate.

The solution did not cause precipitation of any product upon acidification with HCl to a pH of 2.0. Concentration of the acidified reaction mixture results in the formation of viscous hygroscopic syrups that are contaminated with NaCl.

Concentration of the original alkaline reaction liquor containing tetrasodium salt results in a gelatinous sludge which resists solidification or crystallization.

The incorporation of the propylene-2,3-diol group to ethylenediamine bis-N,N'-succinic acid was also achieved by the use of glycidol.

EXAMPLE XXIII

Ethylenediamine Bis-N,N'-2,3-Dihydroxypropane Bis-N,N'-Succinic Acid

73 g. (0.25 mole) of ethylenediamine bis-N,N'-succinic acid were dissolved in 100 ml. of water containing 80 g. of 50% NaOH (1.0 mole). The pH was adjusted to 10.50. 37 g. (0.5 mole) of glycidol were added dropwise to the agitated solution. The temperature rose from 30° C. to 48° C. The liquor was set aside for 16 hours. It was warmed to 90° C. and cooled to room temperature. This solution of tetrasodium salt was passed through a cation exchange column of an acid form. The acidic effluent was concentrated in vacuo to 150 ml. This was further concentrated over calcium chloride in a vacuum desiccator. The product remained as a viscous oil after 6 weeks. Cooling and treatment with solvents such as acetone or ethanol does not solidify or crystallize the hygroscopic residue.

EXAMPLE XXIV

Dibarium Ethylenediamine Bis-N,N'-2,3-Dihydroxypropane Bis-N,N'-Succinate

A 200 ml. aliquot (0.1 mole) solution of 0.5 molar tetrasodium ethylenediamine bis-N,N'-2,3-dihydroxypropane bis-N,N'-succinate was treated with 55 g. (0.2 mole) of barium acetate monohydrate. The solution was stirred

until nearly clear, filtered, treated with 400 ml. of ethanol, and then stirred for 1/2 hour. The product was filtered dry, dissolved in 150 ml. of water, and reprecipitated with 400 ml. of ethanol. The white slurry was filtered and dried under vacuo at 80° C. to a constant weight. A yield of 64 g. was obtained, 90% of the theoretical yield of 71 g.

Analytical data.—C₁₆H₂₄N₂O₁₂Ba₂—Percent N: Found 3.62, theory 3.93%. Percent ash: Found 56.17, theory 55.54% as BaCO₃. Percent Ba: Found 39.85, theory 39.78%.

EXAMPLE XXV

1,8-Hexamethylenediamine Bis-N,N'-2,3-Dihydroxypropane Bis-N,N'-Succinic Acid ("HDHPDS")

70 g. (0.2 mole) of hexamethylenediamine bis-N,N'-succinic acid (I) were dissolved in 100 ml. of water containing 64 g. of 50% by weight NaOH. This solution was stirred, its pH adjusted to 11.0, and heated to 60–65° C. While maintaining these conditions, 44 g. (0.4 mole) of 1-chloro-2,3-propanediol were added alternately with 32.0 g. of 50% NaOH over a 1 hour period. The resulting solution was cooled to room temperature, filtered, and diluted to 500 ml. The clear solution is equivalent to 0.4 molar tetrasodium hexamethylenediamine bis-N,N'-2,3 dihydroxypropane bis-N,N'-succinate (II).

EXAMPLE XXVI

Ethylenediamine Bis-N,N'-3-Hydroxypropane Bis-N,N'-Succinic Acid ("EHPDS")

75 g. (0.25 mole) of ethylenediamine bis-N,N'-succinic acid were dissolved in 100 ml. of water containing 80 g. of 50% NaOH (1.0 mole). The solution was refluxed gently while 52 g. of 1-chloro-3-propanol (0.5 mole) were added dropwise thereto. In the meantime, the solution was maintained at a pH of 10.5–11.0 to Nile blue by the portion-wise addition of a total of 100 g. of 25% by weight NaOH. When the reaction was complete, the mixture was digested for 1/2 hour, cooled, and acidified with 85 ml. of concentrated HCl (1.0 mole) to a pH of 2.0. The product was allowed to settle overnight, was then filtered, washed with 50 ml. of water, washed with 50 ml. of ethanol, and was air-dried to a constant weight. A yield of 28 g. was obtained, 29% of the theoretical yield of 96 g.

Analytical data.—C₁₆H₂₈N₂O₁₀—Percent N: Found 7.11, theory 6.86%.

Titration.—Mol. wt.: Found 339, theory 409. Inflections at pH values of 5.5, 8.5, 11.25.

19
EXAMPLE XXVII

Ethylenediamine Bis-N,N'-Tetraglycol Bis-N,N'-Succinic Acid ("EDTGDS")

292 g. (1.0 mole) of ethylenediamine bis-N,N'-succinic acid were added to 900 g. of triethanolamine (6 moles) containing 100 g. of water. The thick slurry was warmed on an oil bath and gently refluxed to a clear liquid. Over a 3 hour period, 420 g. (2 moles) of polyglycol chloride (#210, Union Carbide Chemical Co.) were added. Heating was continued for 8 hours.

The resulting thick brown liquid was cooled to room temperature, diluted with 2 liters of ethanol and 330 ml. of concentrated HCl. The slurry was cooled to 5° C., filtered, and washed with 500 ml. of ethanol. The mother liquor was boiled free of ethanol while maintaining a 2 liter volume with water. The product exhibited great surface-active properties.

The solution was cooled, adjusted to 2.0 liters with water and was stored as a 0.5 molar solution of ethylenediamine bis-N,N'-tetraglycol bis-N,N'-succinic acid. It was identified in the form of an insoluble zinc salt.

EXAMPLE XXVIII

Dizinc Ethylenediamine Bis-N,N'-Tetraglycol Bis-N,N'-Succinate

A 200 ml. aliquot solution of the acid product of Example XXVII was treated with 200 ml. of 1.0 molar ZnCl_2 with stirring. 32 g. of 50% NaOH were then added. The resulting white precipitate was allowed to settle at 5° C. overnight. It was then filtered, washed with 100 ml. of water, washed with 50 ml. of ethanol, and dried under vacuo at 110° C. to a constant weight. A yield of 40 g. was obtained, 52% of the theoretical yield of 77 g.

Analytical data.— $\text{C}_{26}\text{H}_{26}\text{N}_2\text{O}_{16}\text{Zn}_2$ —Percent N: Found 3.45, theory 3.61%.

EXAMPLE XXIX

Ethylenediamine Bis-N,N'-2-Hydroxy-2-Phenylethane Bis-N,N'-Succinic Acid ("EDPEDS")

146 g. (0.5 mole) of ethylenediamine bis-N,N'-succinic acid were dissolved in 500 ml. of water containing 160 g. of 50% by weight NaOH (2.0 moles). The solution (pH of 11.0) was warmed to 70° C., and then, 5 while vigorously stirring, was treated by the dropwise addition of 120 g. of styrene oxide (1 mole). When all the epoxide dissolved, the solution was digested at 95° C. for 1 hour, cooled to room temperature, and was extracted with 100 ml. of ether. The aqueous yellow liquor was diluted with water to 1 liter and after 1 week was decanted to remove insolubles. The clear liquor represents an 0.5 molar solution of the tetrasodium salt of ethylenediamine bis-N,N'-2-hydroxy 2-phenylethane bis-N,N'-succinic acid.

15 A 200 ml. aliquot (0.1 mole) solution was acidified with 35 ml. (0.4 mole) of concentrated HCl. The product separated as a yellow oil. It was washed with 1 liter of water. It was then dried in a vacuum oven at 20 90° C. to a constant weight. A mass foamed, which hardened to a hygroscopic brittle mass. First crop: 34 g. yield, 72% of the theoretical 47 g. yield.

25 *Analytical data.*— $\text{C}_{26}\text{H}_{32}\text{N}_2\text{O}_{10}$ —Percent N: Found 5.07, theory 5.26%.

20 *Titration.*—Mol. wt.: Found 564, theory 532. Inflection at a pH of 10.70.

EXAMPLE XXX

Ethylenediamine Bis-N,N'-3-Phenoxy 2-Hydroxypropane Bis-N,N'-Succinic Acid ("EDPHPDS")

35 146 g. (0.5 mole) of ethylenediamine bis-N,N'-succinic acid were dissolved in 500 ml. of water containing 160 g. of 50% by weight NaOH (2.0 moles). The solution (pH of 11.0) was warmed to 70° C., then, while stirring rapidly, was treated by the dropwise addition of 150 g. of glycidol phenyl ether (1.0 mole). When all 50 the epoxide had dissolved, the solution was digested at 55 95° C. for 1 hour, cooled to room temperature, and extracted with 100 ml. of ether. The resulting clear liquor was diluted to 1 liter, and, after several days, decanted free of insolubles. This clear liquor represented a 0.5 60 molar solution of the tetrasodium salt of ethylenediamine bis-N,N'-3-phenoxy 2-hydroxypropane bis-N,N'-succinic acid.

65 A 300 ml. aliquot solution of the reaction liquor (0.15 mole) was acidified with 50 ml. of concentrated HCl (0.6 mole). A white syrup separated out. The syrup was washed with 1 liter of water and was dried under vacuo at 90° C. to a constant weight. The product foamed, then hardened to a hygroscopic brittle mass. 70 A yield of 45 g. was obtained, 83% of the theoretical yield of 54 g.

75 *Analytical data.*— $\text{C}_{26}\text{H}_{36}\text{N}_2\text{O}_{12}$ —Percent N: Found 4.71, theory 4.73%.

70 *Titration.*—Mol. wt.: Found 616, theory 592. Inflection at a pH of 10.60.

21
EXAMPLE XXXI

Ethylenediamine Bis-*N,N'*-Succinic Bis-*N,N'*-Acetic Acid ("EDDSDA")

146 g. (0.5 mole) of ethylenediamine bis-*N,N'*-succinic acid were dissolved in 200 ml. of water containing 160 g. of 50% NaOH (2.0 moles). The solution was stirred and was heated in a beaker to 50° C. 100 g. (1.06 mole) of chloroacetic acid were slowly added to the solution along with 160 g. of 50% NaOH while maintaining the pH at 10.5-11.0 (Bogen's indicator). The temperature of the reaction solution rose to 100° C. (cooling may be required to prevent the reaction mixture from boiling out of the vessel). When the reaction was complete, the solution was cooled and acidified to a pH of 1.5 with 240 ml. of concentrated HCl. The product separated-out overnight, was filtered, was washed with 50 ml. of water, and was dried below 80° C. to a constant weight. A yield of 140 g. was obtained (M.P. 212-218° C.), 70% of the theoretical yield of 202 g. (as dihydrate).

Drying the dihydrate at 80° C. or more causes decomposition, and drying in vacuo below 80° C. removes the theoretical amount of hydrated water.

The product, a white crystalline solid, was slightly soluble in water, soluble in strong aqueous acids and alkalies, but insoluble in acetone, alcohol, benzene and many common organic solvents. It sequesters in alkaline solutions calcium, magnesium, copper, etc.

Analytical data. — $\text{C}_{14}\text{H}_{20}\text{N}_2\text{O}_{12} \cdot 2\text{H}_2\text{O}$ — Percent N: Found 6.28, theory 6.31%.

Titration.—Mol. wt.: Found 448, theory 444. Inflection at pH values of 5.75, 8.5, 11.0 (4th, 5th and 6th COOH groups).

EXAMPLE XXXII

Octasodium Ethylenediamine Bis-*N,N'*-Methanephosphonate Bis-*N,N'*-Succinate ("EDMPDS")

292 g. (1.0 mole) of ethylenediamine bis-*N,N'*-succinic acid were dissolved in 500 ml. of water containing 320 g. of 50% NaOH (4.0 moles). The solution was then treated with 308 g. of 84% chloromethanephosphonic acid (2.0 moles), and 320 g. of 50% NaOH (4.0 moles). The reaction solution was refluxed in a stainless steel container while the pH was kept at 11.0-11.5 (pHydron paper); 160 g. of 50% NaOH were consumed. The total reflux time was 24 hours.

When an aliquot of reaction solution was acidified to a pH of 1.5 with concentrated HCl, it did not yield the solid free acid; similar results were obtained when the solution was further treated with acetone or ethanol. Concentration of the alkaline reaction liquor yields a mushy slurry which does not solidify or crystallize. Since neither the free acid nor sodium salt was isolated, identification was carried out with an insoluble salt thereof.

22
EXAMPLE XXXIII

Tetrabarium Ethylenediamine Bis-*N,N'*-Methanephosphonate Bis-*N,N'*-Succinate

A 200 ml. aliquot solution of octasodium salt (0.1 mole) was added to 600 ml. of water. 400 ml. of 1.0 molar BaCl₂ solution were then added while stirring the solution. The slurry was stirred for 1 hour, filtered, washed with 100 ml. of water, washed with 100 ml. of ethanol, and was then dried at 115-120° C. for 5 hours. A yield of 76 g. was obtained, 75% of the theoretical yield of 102 g.

Analytical data. — $\text{C}_{12}\text{H}_{14}\text{N}_2\text{O}_{14}\text{P}_2\text{Ba}_4$ — Percent N: Found 2.55, theory 2.68%. Percent Ba: Found 51.5, theory 53.7%.

EXAMPLE XXXIV

Meta-Dixylyl- α,α' -Diamine Bis-*N,N'*-Succinic Bis-*N,N'*-Acetic Acid ("XDADS")

184 g. (0.5 mole) of m-dixylyl- α,α' -diamine bis-*N,N'*-succinic acid were dissolved in 200 ml. of water containing 160 g. of 50% by weight NaOH. The pH was kept at 11.0 while the temperature was raised to 80° C. 100 g. (1.05 moles) of chloroacetic acid and 170 g. of 50% NaOH were slowly added to and blended with the solution while maintaining a maximum temperature of 95° C. by cooling the reaction mixture. The resulting liquor was digested at 95° C. for 1/2 hour, was cooled, and diluted to 1 liter. This solution contained 0.5 molar hexasodium m-dixylyl- α,α' -diamine bis-*N,N'*-diacetic-bis-*N,N'*-disuccinate.

EXAMPLE XXXV

Our products are exceptional chelants or chelating agents, as evidenced by the data shown in Table II, infra. 60 Table II shows instances in which effective chelation was observed when 0.001 mole of metal ions were treated with from 0.001 to 0.002 mole of specified chelant in 50 ml. of water at the designated pH. Excess chelant is used to compensate for the use of products that may have a purity of less than 100%. A trace (e.g. 1-2 drops of saturated Na₂HPO₄ solution) of orthophosphate was added to induce precipitation where the chelating action was weak. The chelates have a mole ratio of chelant to metal ion of 1:1.

70 The "+" symbol in Table II indicates positive chelation, which is evidenced by the lack of normal precipitation under the specified conditions. The " $\pm$ " symbol designates that a precipitate forms after several hours. The pH values of the various test solutions are designated 75 at the bottom of Table II.

TABLE II

Chelant	Example	METAL IONS															
		Al ⁺⁺⁺	Ce ⁺⁺⁺⁺	Co ⁺⁺	Cr ⁺⁺⁺	Fe ⁺⁺⁺	Mn ⁺⁺	Ba ⁺⁺	Ca ⁺⁺	Cu ⁺⁺	Mg ⁺⁺	Pb ⁺⁺	Th ⁺⁺	Th ⁺⁺⁺	Zr ⁺⁺	Zr ⁺⁺⁺	Zn ⁺⁺

pH (where a * is indicated)					*13.0	*12.0	*14.0							*12.0			

NOTE.—+ equals positive chelation, ± equals precipitate forms after several hours.

The ability of the above products shown in Table II, above, to form stable water-soluble chelates with multivalent metal ions has been well established. This property along with others makes these compounds particularly suitable for such fields as water treatment, metal cleaning and treatment, antioxidants, dyeing and textile treatment, rubber and resin formulation, petroleum refining, mineral recovery and purification, pharmaceutical uses, analytical uses, agricultural uses, and radio-decontamination, and many others.

EXAMPLE XXXVI

The products of this invention were found to be quite effective in removing rust and oxide coatings from metal surfaces in aqueous solutions having a pH below 9.0 and containing a reducing agent such as sulfite, thiosulfate, sugar, hydroquinone, etc. For example, fresh uniformly rusted iron strips having a 81.6 cm.² surface were immersed for three hours at 75° C. without agitation in a cleaning solution having the following formulation:

EDDSDE (Example IX) g. 10
Sodium bisulfite (58.5% SO₂) g. 5
Water was added to bring the volume to 200 ml.
pH (adjusted with NaOH) 8.0

Table III, infra, shows the weight of rust removed from the 81.6 sq. cm. surface of the test strip along with the condition of the surface.

TABLE III

Compound	Example	Weight rust lost (g.) at a pH at 8.0	Comment
EDDSDE	IX	0.5050	Clean surface.
DTHDS	XIX	0.3290	Do.
TPHDS	XX	0.4600	Do.
EDPPDS	XXII	0.3720	Do.
HDHPDS	XXV	0.3180	Spotted rust.
EHPDS	XXVI	0.3660	Do.
EDTGDS	XXVII	0.2305	Heavy rust.
EDPEDS	XXIX	0.6000	Do.
EDPHPDS	XXX	0.3810	Spotted rust.
EDDSDA	XXXI	0.3590	Clean surface.
EDMPDS	XXXII	0.3780	Do.
XDADS	XXXIV	0.4620	Do.

At a pH of 8.0, much of the rust was removed by flaking, and left insoluble particles suspended in the cleaning bath.

The next, a second, series of tests were conducted in same manner, except the test solutions were adjusted to a pH of 7.0 instead of pH 8.0. The results of these tests are shown in Table IV, infra. The asterisks in Table IV indicate that rust was completely dissolved, resulting in a clear bath and clean metal surface.

25

TABLE IV

[Rust removal at a pH of 7.0]

Compound	Example	Weight rust lost (g.)	Comment
EDDSDE	IX	0.5650	Clean surface.*
DTHDS	XIX	0.5821	Do.*
TPHDS	XX	0.5540	Do.*
EDPPDS	XXII	0.4930	Do.*
HDHPDS	XXV	0.4360	Light rust.
EHPDS	XXVI	0.1450	Heavy rust.
EDTGDS	XXVII	0.2390	Do.
EDPEDS	XXIX	0.2320	Do.
EDPHPDS	XXX	0.2550	Do.
EDDSDA	XXXI	0.5370	Clean surface.*
EDMPDS	XXXII	0.5230	Do.*
XDADS	XXXIV	0.4020	Do.*

*Rust was completely dissolved, resulting in a clear bath and clean metal surface.

40 A comparison of Tables III and IV shows that the pH of 7.0 was more effective than 8.0 for the efficient rust removal and maintenance of bath clarity.

EXAMPLE XXXVII

45 The products of our invention were found to inhibit mineral acid attack on plain iron. While most of the compounds were moderately effective, two members (see Examples XXIX and XXX) were particularly outstanding. The acid used was 704 g. or 500 ml. of 50% by 50 weight H₂SO₄. The test strip had a total surface area of 76 sq. cm. The tests were at room temperature, and the attack was measured in i.p.y. (inches of penetration per year).

TABLE V

Compound	Example	G. of product added	Percent based on acid	I.P.Y.
EDPEDS	XXIX	0.10	0.028	0.823
EDPEDS	XXXI	0.25	0.071	0.240
EDPEDS	XXIX	0.50	0.142	0.035
EDPHPDS	XXX	0.10	0.028	0.973
EDPHPDS	XXX	0.25	0.071	0.240
EDPHPDS	XXX	0.50	0.142	0.037
Blank (acid only)				1.356

EXAMPLE XXXVIII

75 Formulations of urea-formaldehyde in water were found to "set" shortly after 3-4 hours. The addition of a small quantity of EDDSDE and the like suppressed this solidification. Typical formulation are shown as Samples I-III, infra:

Sample I

180 ml. of formalin
68 g. of urea
pH of 7.5

25

Sample II

Sample I plus 15 g. of EDDSDE (Example IX)

Sample III

Sample I plus 15 g. of EDPDSS (Example XXII) 5

While Sample I solidified after 3-4 hours, Samples II and III remained fluid for several additional hours. When diluted with 200 ml. of water, the clear liquor of Samples II and III remained fluid many days. This property may be used in prolonging the life of monomers (e.g., dimethylol urea) when preparing various formulations.

EXAMPLE XXXIX

The compounds of this invention may be used to hold 15 the metal in electrolytic plating or "strike" baths. The plating ions (chelated) deposit on higher metals. The replaced metal is in turn taken up by the chelant.

A typical bath was made up as follows:

CuSO ₄ ·5H ₂ O	g-	32	20
EDDSDE (Example IX)	g-	100	
Wetting agent	g-	0.5	
pH (adjusted with NaOH)		5.0	
Temperature	°C-	50	25

A clean strip of iron, 225 sq. cm. surface area, was immersed in the above bath for 15 minutes. An adherent, even coating of copper was formed. It was found to weight 0.0246 g. and have a 1.226×10^{-5} cm. thickness.

EXAMPLE XXXX

Plants growing in chlorosis producing calcareous soils were found to respond rapidly to treatment with EDDSDE·FeNa. A sample preparation of the ferric chelate follows:

EDDSDE	362 g. (as monolactone).
H ₂ O	500 ml.
NaOH, 50%	320 g.

The above ingredients were mixed, cooled to room temperature, and, while stirring rapidly, 333 ml. of 1.5 molar Fe₂(SO₄)₃ were added. The red-brown liquor was cooled to 0° C., decanted free of Na₂SO₄·10H₂O, and used as such.

Tests showed that the application of 50-125 p.p.m. Fe to soil having red kidney bean plants growing therein, resulted in the greening of the plants and at least in part caused the soil to yield a good crop of beans. (There were good results with 50 p.p.m. Fe and no signs of toxicity with 125 p.p.m. Fe.) Untreated plants (control) were yellow or light green with small or spindly bean production.

Avocado seedlings in chlorotic soils showed no signs of chlorosis when the soil was treated with 100 p.p.m. Fe.

Chlorotic gardenias became completely green following the treatment of the soil with EDDSDE·FeNa. The old leaves turned green, and new bright green leaves appeared. Sunflower plants and citrus seedlings also favorably responded to 150 p.p.m. Fe. Excellent results are obtained with EDDSDE·FeNa, using 60 p.p.m. Fe. Smog damaged plants treated with ethylenediamine tetracetic ferric chelate much more than those treated with EDDSDE·FeNa.

The foregoing detailed description has been given for clearness of understanding only, and no unnecessary limitations should be understood therefrom, as modifications will be obvious to those skilled in the art.

We claim:

1. A compound selected from the group consisting of:

(a) a compound of the formula

26

wherein A₁ and A₂ are members of the group consisting of lower alkylene and lower alkylene-phenylene-lower alkylene groups; Y₁, Y₂, and Y₃ are members of the class consisting of alkyl, alkylaryl, hydroxyalkyl, hydroxyalkylaryl, hydroxyalkyloxyaryl, carboxyalkyl, alkylcarboxylate, hydroxyalkylpolyoxyalkyl, alkylphosphonic acid, alkylphosphonate, alkylsulfonic acid, alkylsulfonate, and hydrogen groups, and at least one of Y₁ and Y₂ is not hydrogen; k is a positive integer of not less than 1 and not more than 7; Z₁ and Z₂ are saturated acyclic bis-adduction groups derived from the class consisting of lower alkenyl 1,4 conjugated polycarboxylic acids having at least 2 and not more than 3 carboxyl groups, and salts thereof;

- (b) chelates of the product of (a) and a polyvalent metal ion; and
(c) esters of the product of (a) and a lower alkyl group.

2. A compound of the formula:

wherein A₁ and A₂ are members of the group consisting of lower alkylene and lower alkylene-phenylene-lower alkylene groups; Y₁, Y₂, and Y₃ are members of the class consisting of alkyl, alkylaryl, hydroxyalkyl, hydroxyalkylaryl, carboxyalkyl, alkylcarboxylate, hydroxyalkylpolyoxyalkyl, alkylphosphonic acid, alkylphosphonate, alkylsulfonic acid, alkylsulfonate, and hydrogen groups, and at least one of Y₁ and Y₂ is not hydrogen; k is a positive integer of not less than 1 and not more than 7; Z₁ and Z₂ are saturated acyclic bis-adduction groups derived from the class consisting of lower alkenyl 1,4 conjugated polycarboxylic acids having at least 2 and not more than 3 carboxyl groups, and salts thereof.

3. The product:

4. The product:

5. The product:

wherein (a) x is a positive integer of 1-6, (b) each lower alkylene radical in the bracketed moiety may differ, and (c) each repeating bracketed moiety may differ from the preceding one.

6. The product:

wherein M¹, M², M³, and M⁴ are members of the group consisting of hydrogen, salt forming substituents and lower alkyl substituents.

7. The product:

wherein M^1 and M^2 are members of the group consisting of hydrogen, salt forming substituents and lower alkyl substituents.

8. The product:

wherein M^1 and M^2 are members of the group consisting of hydrogen, salt forming substituents and lower alkyl substituents.

9. The product:

wherein M^1 and M^2 are members of the group consisting of hydrogen, salt forming substituents and lower alkyl substituents.

10. The product:

wherein M^1 and M^2 are members of the group consisting of hydrogen, salt forming substituents and lower alkyl substituents.

11. The product:

wherein M^1 and M^2 are members of the group consisting of hydrogen, salt forming substituents and lower alkyl substituents.

12. The product:

wherein M^1 , M^2 , and M^3 are members of the group consisting of hydrogen, salt forming substituents and lower alkyl substituents.

13. The product:

wherein M^1 , M^2 , and M^3 are members of the group consisting of hydrogen, salt forming substituents and lower alkyl substituents.

14. The product:

wherein M^1 , M^2 , M^3 , M^4 , M^5 , and M^6 are members of the group consisting of hydrogen, salt forming substituents and lower alkyl substituents.

15. Chelate of a compound of claim 2 and polyvalent metal ion.

16. Ester of a compound of claim 2 and lower alkyl radical.

17. Metal salt of the product of claim 3.

18. Chelate of the product of claim 3 and polyvalent metal ion.

19. Ester of the product of claim 3 and lower alkyl radical.

20. Metal salt of the product of claim 4.

21. Chelate of the product of claim 4 and polyvalent metal ion.

22. Ester of the product of claim 4 and lower alkyl radical.

23. Metal salt of the product of claim 5.

24. Chelate of the product of claim 5 and polyvalent metal ion.

25. Ester of the product of claim 5, and lower alkyl radical.

UNITED STATES PATENT OFFICE
CERTIFICATE OF CORRECTION

Patent No. 3,077,487

February 12, 1963

William M. Ramsey et al.

It is hereby certified that error appears in the above numbered patent requiring correction and that the said Letters Patent should read as corrected below.

In the grant, lines 1 and 2, and in the heading to the printed specification, line 7, for "Charles Kerzerian", each occurrence, read -- Charles Kezerian --; column 2, lines 63 and 73, the term "radical" presently included in each of the formulas shown should appear in the same type size as the body of the specification and not in the smaller type size of the formulas; column 3, lines 49 and 50, for

read

column 25, line 54, for "gardenitas" read -- gardenias --; column 26, line 3, for "groups:" read -- groups; --.

Signed and sealed this 10th day of December 1963.
